UNITED STATES PATENT OFFICE.

HENRY FLAD, OF ST. LOUIS, MISSOURI.

IMPROVEMENT IN HYDROSTATIC ELEVATORS.

Specification forming part of Letters Patent No. 146,663, dated January 20, 1874; application filed May 23, 1873.

To all whom it may concern:

Be it known that I, HENRY FLAD, of St. Louis, St. Louis county, Missouri, have invented an Improvement in Hydrostatic Elevators, of which the following is a specification:

The first part of my improvement relates to what I denominate a "multiplier." This consists of a compound ram, having a larger piston combined with a smaller piston or plunger, working in separate cylinders or chambers, by which the water or other liquid acted on by the smaller piston is placed under greater pressure than that of the water acting on the larger piston, by which the smaller piston is actuated in proportion to the relative face areas of the two pistons. The chamber in which the smaller piston or plunger plays is in communication with the cylinder of the hoisting-ram, which is secured to the elevator-platform. The cylinder of the latter ram and the chamber in communication with it may be filled with oil, glycerine, or other liquid.

The second part of my improvement relates to the means employed to stiffen and guide the platform-plunger. These guides consist of crucial frames, which slide freely on the plunger, and the ends of whose arms carry anti-friction rollers, running on spindles at the corners of the trunk in which the platform travels. The upper guide-frame is supported by rods depending from the upper platform, and sliding in vertical sockets in the frame, and having at the lower ends heads, on which the frame is suspended and raised with the platform after the latter has traveled up a certain distance; and each guide-frame in its turn is picked up by rods depending from the frame next above it, so that as the platform is elevated and a greater length of the plunger becomes exposed above the stuffing-box of the cylinder, it shall have side support at different elevations by means of the guide-frames; and as the platform descends, the guide-frames will, one at a time, settle down upon the top of the stuffing-box or other support beneath the platform when in its lowest position.

The third part of my invention relates to the means employed to balance the platform, plunger, &c. This consists of a rope, which extends from the platform, and is attached to

a drum, to which is secured a grooved fusee-pulley, that has fastened to it a rope, which coils thereon, and to the free end of which is attached a weight to partly counterbalance the platform, plunger, and guides. The arrangement is such that as the platform and plunger ascend, and the guides are one after another taken up, thus adding to the weight suspended by the platform-rope, the counterbalance-weight shall uncoil from the fusee, commencing from the smaller end, so that as the platform rises and the counterbalance-weight descends the latter shall exert an increasing rotating influence on the drum, equivalent to the increasing weight of platform attachments. It will be seen that as the counterbalance-weight descends its point of suspension on the fusee is more distant from the axis.

In the drawings, Figures 1 and 2 are axial sections at right angles to each other.

A is the cylinder of a hydrostatic ram, having water-supply and discharge pipe a, that communicates with the waste-pipe a', and also with a pipe, a'', in communication with the city water-supply, or other supply of water under pressure. The pipe a is supplied with a three-way cock, b', or other well-known device, worked by a hand-rod, B, so as to put the lower end of the cylinder A in communication with either the supply or waste pipe, to cause the ascent or descent of the platform, or to close connection between the cylinder and both pipes, so as to hold the platform stationary. b is a counter-balance to rod B. C is the plunger, having a head, c, packed at the periphery, and working in the cylinder A, which has at the upper end an air-orifice, a''', to allow the passage of air to and from the part of the cylinder above the piston-head c. The body of the plunger works through a head, D, in leather or other packing d, working up and down in a chamber or cylinder, E, which is in communication by a pipe, f, with the cylinder F of the hoisting-ram. G is the plunger, attached directly to the platform H, and working in the cylinder F through a stuffing-box, g. The cylinder F would usually enter the earth a considerable distance, as it and the plunger would necessarily have a length about equal to the distance traveled by the platform. The plunger G may be tubular, in which case

the bottom would be closed. The cylinders E and F may contain oil, glycerine, water, or other suitable liquid, as the quantity should be constant, and, except for leakage, would be unchanged. *e* is a force-pump, by which liquid may be forced into the chamber E to make up for leakage. The weight of the platform and plunger and the guides of the latter is partly counterbalanced by a weight, *I*, attached to a rope, *i*, whose other end is secured to the larger end of a grooved fusee-pulley, *K*. The fusee is attached to a drum, *L*, on which is coiled, and to which is secured, the rope *l*, one end of the rope being secured to the drum and the other end to the platform at *h*. The rope may run over a grooved pulley interposed between the platform and the drum, so as to keep its descending part vertical, the drum being located some distance from the pulley; or the verticality of the descending part of the rope may be accomplished in any well-known manner. A preponderance of weight has, of course, to remain on the side of the platform, to drive the fluid out of the cylinder F in descending, when a multiplier is used. Depending from the platform-bottom are rods *M*, passing through the arms *n* of a crucial frame, *N*, through whose butt or center passes the plunger *G*, the frame *N* sliding freely on the rods *M* and the plunger, and being raised by the platform (after the latter has traveled up from its lowest position a certain distance, the length of the rods *M*) by the heads *m* of the rods coming in contact with the bottom of the frame. The arms *n* of the frames *N* carry at their ends anti-friction rollers *o*, which travel up and down vertical guides *O*, that may occupy the corners of the trunk in which the platform travels. Depending from that guide-frame *N* next to the platform are rods *M*, which pass through a second frame, *N*, similar to that described, and from this is supported another similar guide-frame, and so on, if the height renders it necessary to stiffen the plunger *G* as it becomes exposed more and more from its cylinder *F*. Where the pressure of the water is sufficiently great, the multiplier *A C e E* may be dispensed with, and the ram *G* operated directly from the water-supply. Where the pressure of the supply water is insufficient to operate the ram *G* by direct action upon it, the piston-head *e* must have an area so much

greater than the sectional area of the body *C* as to give the required pressure on the liquid in the chamber *E* and cylinder *F* to raise the platform and load. The plunger or column *G* would, of course, have sufficient strength to sustain the platform in case of the breakage of the rope *l* or *i*, and so long as this column itself is not destroyed, no breakage of other parts of the machinery would have dangerous results, because the rate of descent of the platform would be limited by the rate of outflow of the water from the cylinder *A* or *F*, as the case might be. In the efflux-pipe may be introduced a conical check-valve, whose opening is reduced by increased pressure, so as to let the load down easily and without danger in case one of the ropes carrying the counter-weight or platform should be broken while the load is descending. By providing a small elevated tank, into which the water would be forced in lowering loads, the platform by itself, or even with the addition of a light load, may be raised without the use of any fresh supply of water, and consequently without any cost. In this case the water-supply cock or valve *b'* may be closed, and the same water may be used over and over again, as long as the descending loads are heavy and the ascending loads light.

I claim as my invention—

1. The multiplier consisting of a larger piston, *c*, and a smaller piston or plunger, *C*, connected together and working in separate cylinders or water-chambers *A E*, by which the pressure of the water or other liquid acted on by the smaller piston is rendered greater than that of the liquid acting on the larger piston, substantially as set forth.
2. The combination of the elevator-platform *H*, ram *G F*, and multiplier *A C e E*, substantially as set forth.
3. The guides *N*, in combination with the plunger or ram *G*, arranged substantially as set forth.
4. The combination of the ram *G*, platform *H*, guides *N*, ropes *l* and *i*, fusee *K*, and weight *I*, substantially as set forth.

HENRY FLAD.
